UNITED STATES PATENT OFFICE.

ALFRED CLARKE AND HAVEN C. PERHAM, OF LOWELL, MASSACHUSETTS,
ASSIGNORS TO THE KITSON MACHINE COMPANY, OF SAME PLACE.

MACHINE FOR OPENING AND CLEANING COTTON AND OTHER FIBERS.

SPECIFICATION forming part of Letters Patent No. 312,815, dated February 24, 1885.

Application filed June 18, 1883. (No model.)

To all whom it may concern:

Be it known that we, ALFRED CLARKE and HAVEN C. PERHAM, citizens of the United States, residing at Lowell, in the county of Middlesex and Commonwealth of Massachusetts, have invented certain new and useful Improvements in Machines for Opening and Cleaning Textile Fibers, of which the following is a specification.

- 10 Our invention relates to machines for opening and cleaning textile fibers; and it consists in certain novel combinations of the parts of such machines, substantially as hereinafter described and claimed.
- 15 In the accompanying drawings, Figure 1 is a cross-section of a beater provided with a perforated tubular shaft; Fig. 2, a longitudinal section of the same and its driving-pulley; Fig. 3, the same as Fig. 1, with the addition 20 of pipes or hollow guards inserted in the perforations; Fig. 4, a central longitudinal section of a part of the beater and of a pipe and a fan-blower; Fig. 5, a partial side elevation of a lapper containing such a beater.
- 25 A is the frame of the lapper; B B', apron-rolls; C, the apron; D, an apron-side; E E', feed-rolls; F, a beater-shaft; F', its arms; F², its blades; F³, a driving-pulley secured to the beater-shaft, by means of which the beater is 30 caused to rotate by a belt from an overhead counter-shaft; G, the beater-grate; H H', lap-collecting wire cages; I I', drawing-rolls; J J', J², calender-rolls; K K', lap-rolls; L, rotary exhaust-fan; T T', exhaust-pipes to lead the 35 air from the wire cages to the fan, all the above-named parts being of the usual construction and operation except the beater, which, instead of having, as usual, a solid shaft, has instead a hollow or tubular shaft, 40 F, which shaft has perforations or holes F³ between its arms F'. The object of these holes is to allow the air which enters the shaft at one or both ends to be thrown out by centrifugal force when the shaft is revolved rapidly.
- 45 To make the flow of air stronger and more certain, there are pipes or hollow guards F⁴, which project from said holes F³ and are curved backward—that is, contrary to the direction 50 of the rotation of the beater—so that the rotation of the beater will throw the air out with

considerable force. The force with which the air is expelled through the holes is increased by a blast of air from a rotary blower, N, directed through a pipe, N', leading into one or both ends of the beater-shaft. Of course, if the air is blown into only one end of the beater-shaft, the other end of the shaft should be plugged up or closed.

The blower N is of any usual construction.

The object of causing the air to stream out through the projections in the shaft is to better prevent the fibers from lodging on the ends of the beater-arms and on the blades of the beater, and also to better assist the passage of the fibers from the beater to the lap-collecting cages, and to better aid to accomplish in a more satisfactory manner what is now done by the exhaust-fan L and pipes T T', which, by taking the air from the inside of the cages, cause the air to rush through the wire covering thereof into the same, carrying the dust into said cages and out through the exhaust-pipes and fan-case into the usual dust-receptacles, and leaving the fibers upon the outer surfaces of the cages, which, by their revolution, form the fibers into a sheet between them.

The beater, as heretofore used, by its rapid revolution, has a tendency to compress the air in front of the beater-blades, and to create a vacuum behind the blades and at the center of the beater, and thereby to cause the fibers to circulate around with the beater, producing curling and "stringing" of the fibers—by "stringing" meaning a twisting and matting of the fibers together. This curling and stringing is prevented by admitting sufficient air to the middle of the beater in the manner hereinbefore described. The air is commonly admitted to the beater underneath or through the front beater-grates, and by the operation of the beater on the fibers the heavier refuse falls through the grates; but the inrushing air takes the lighter dust back into the machine and does not extract it from the fibers. By admitting air through the shaft of the beater, as herein described, this difficulty is obviated.

Instead of a pair of lap-collecting cages, a single cage with a roll, in place of the other cage, may be used in the well-known manner without departing from the spirit of our invention, this single cage and auxiliary roll or

a pair of cages performing the same function, and we term either a set of "lap-collecting cages."

We claim as our invention—

5 1. A beater provided with a hollow shaft having one or more perforations, said shaft being open at one or both ends, and means, substantially as described, for supplying a continuous current of air to said perforations through said hollow shaft, as and for the purpose specified.

15 2. The combination of the beater provided with a hollow perforated shaft open at one or both ends, means, substantially as described, for supplying a continuous current of air to said perforations through said hollow shaft, and a set of lap-collecting cages, as and for the purpose specified.

20 3. The combination of the beater provided with a hollow perforated shaft open at one or both ends, means, substantially as described, for supplying a continuous current of air to said perforations through said hollow shaft,

and a set of lap-collecting cages, and the fan for exhausting said cages, as and for the purpose specified.

4. The combination of the perforated hollow shaft open at one or both ends, the arms secured to said shaft, and beater-blades secured to the outer ends of said arms, and outwardly-extending pipes communicating with the interior of said shaft and open at their outer ends, and means for rotating said beater, as and for the purpose specified.

35 5. The combination of a beater provided with a perforated hollow shaft and outwardly-extending pipes, the outer ends of said pipes being bent in a direction contrary to the direction of the rotation of said beater, and means for rotating said beater, as and for the purpose specified.

ALFRED CLARKE.
HAVEN C. PERHAM.

Witnesses:

ALBERT M. MOORE,
JOSEPH Y. BRADBURY.

It is hereby certified that in Letters Patent No. 312,815, granted February 24, 1885, upon the application of Alfred Clarke and Haven C. Perham, of Lowell, Massachusetts, for an improvement in "Machines for Opening and Cleaning Cotton and other Fibers," an error appears in the printed specification requiring the following correction, viz: In line 53, page 1, the word "is" between the words "holes" and "increased" should read *may be*; and that the Letters Patent should be read with this correction therein to make it conform to the record of the case in the Patent Office.

Signed, countersigned, and sealed this 17th day of March, A. D. 1885.

[SEAL.]

M. L. JOSLYN,
Acting Secretary of the Interior.
